COMBINED WATER SPOUT AND EXHAUST STOPPER UNIT FOR A WASHBOWL OR SIMILAR BATHROOM ARTICLE

Julius Hurwitz, Bayside, N. Y.

Application January 9, 1956, Serial No. 39,665

Term of patent 7 years

(Cl. D91—3)

Fig. 1 is a side elevational view of a combined water spout and exhaust stopper unit for a washbowl or similar bathroom article, showing my new design, the opposite side elevational view thereof being the same;

Fig. 2 is a front elevational view thereof; and

Fig. 3 is a top plan view thereof.

I claim:

The ornamental design for a combined water spout

and exhaust stopper unit for a washbowl or similar bathroom article, as shown and described.
